UNITED STATES PATENT OFFICE.

ROBERT HEINRICH, OF RACINE, WISCONSIN.

METAL SHEARS.

Application filed August 6, 1927, Serial No. 211,172.

This invention relates to metal shears and shape cutters.

This invention is an improvement over that disclosed in an application for metal shears, filed May 16, 1927, Serial No. 191,711, in which I am a joint applicant, and has in general the same objects as those set forth in such application.

In sheet metal work it is frequently desirable to form cuts terminating in rounded ends. This work has heretofore been done by drilling the holes in the sheet metal to form the rounded ends and thereafter making straight cuts to the drilled holes.

The object of my invention is to provide a new, scientifically designed cutter that is for use in pattern shops and tool rooms when manufacturing templates and gauges. It cuts sheet metal into any design as easily as 20 a paper shears cuts paper. It cuts template-making costs to a full tenth of former slow inefficient methods.

Furthermore, this metal shears and shape cutter is so accurately designed that it can 25 cut sheet metal into any pattern without necessitating much filing. A few quick, short downstrokes do the work. The concave cutting knife shears along any curved line. The semi-circular punch cuts out the hard-to- 30 get-at corners.

An embodiment of the invention is shown in the accompanying drawings, in which:

Figure 1 is a side elevation partly broken away of the device;

Figure 2 is a sectional view on the line 2-2 of Figure 1;

Figure 3 is a sectional view on the line 3-3 of Figure 1;

Figure 4 is a plan view of the upper blade;

Figure 5 is a view showing a piece of sheet metal cut by means of the shears and illustrating the type of work performed by the shears.

Referring to the drawings, it will be seen 45 that the device comprises a main body portion 1 which is provided with a movable blade 2 pivotally mounted, as indicated at 3, and provided with an operating handle 4. This movable blade, as may be seen from Figure 4, is provided with a rounded outer end 5 for a purpose hereinafter to appear. Preferably, the lower surface of the blade is curved, as shown in Figure 1, so as to get a gradual shearing action from the inner portion of the shears outwardly as the movable blade is forced downwardly.

The body portion 1 is provided with an offset lower portion to which the blade 6 is secured by means of a pair of screws 7. The blade 6 is provided with an inwardly turned lip 8 (see Figure 3) which cooperates with the rounded end 5 of the movable blade 2. The blade 6 is bevelled throughout its length including the rounded or inwardly curved lip 8, as may be seen from Figures 1 and 2. Further, it is to be noted that the opposite edge of the movable blade is also bevelled in the reverse direction, as may be seen from Figure 2. It is to be noted also from Figure 1, that the blade is provided with a cutout 9 extending from the lower edge, as shown in Figure 1, upwardly to approximate its center.

When it is desired to make merely a straight cut without the finish of curved ends, 75 the blade 6 may be reversed to present the straight edge without the inwardly curved lip. This straight edge cooperates with the blade 2 in the usual manner.

It is preferable to provide the metal shears 80 with supporting means whereby it may be either securely gripped in the vise, as described in our copending application, or may be secured to the bench or floor. For instance, a pair of angle iron feet 10 may be secured 85 to the body portion 1, as shown in Figures 1 and 2. These angle iron feet extend continuously on one side from one end of the device to the other and on the other side stop short at the lines indicated by the reference character 11 in Figure 1. This provides an open 90 space on one side of the device. The body portion 1 is provided with a cutout corresponding to the lines 11 and with sockets 12 which receive the trunnions 13 of a wedge 95 shaped pivoted lip 14. This pivoted lip, as may be seen from Figures 1 and 2, is preferably made of two half sections riveted together with a spacing block 15 between them. It is adapted to be gripped between the vise 100 jaws 16 (see Figure 2) and the upward tapering construction will prevent withdrawal of the device when in use. If it is desired to secure the device to the floor or bench, bolts or screws are passed through the apertures in 105 the feet 10 (see Figure 3) and the clip 14 is swung outwardly to the side.

It will be seen that a novel form of metal shears has been provided which will perform operations heretofore jointly performed by 110 means of shears and other tools.

It will be seen further that the device

may be used as the ordinary type of metal shears for cutting straight slots, if desired, or by a suitable adjustment, that is to say, reversal of the stationary blade may be used 5 for cutting slots terminating in rounded ends.

It will be seen further that the device is very simple in construction and is eminent-
ly practical.

10. While I have mentioned in a general way certain shapes which the blades are capable of cutting, it should be distinctly understood that due to this peculiar blade combination I am enabled to cut any desired shape, such 15 as square, hexagon, polygonal, U-shape, half-round, ogee curves, or the like, all of which configurations can be cut in various sizes.

Although the invention has been described in considerable detail, such description is in-
20 tended as illustrative rather than limiting as the invention may be variously embodied and as the scope of such invention is to be determined as claimed.

I claim:

25. 1. A pair of metal shears comprising a rigid body portion, a normally stationary plural-edged blade, having a cut-out in one end thereof extending from one edge of the blade to approximately the longitudinal cen-
30 ter thereof, means for securing said blade

to the body portion with either cutting edge uppermost, a movable blade secured to said body portion and cooperating with the first mentioned blade, said movable blade having a rounded end, an inwardly curved end on 35 the first mentioned blade on one of its cutting edges at one side of the cut-out and having its other cutting edge continuous and straight.

2. A pair of metal shears comprising a 40 rigid body portion, a movable blade piv-
otally secured thereto and provided with a curved end, means for opening said movable blade, a normally stationary blade having cutting edges on opposite sides thereof and 45 formed with a cut-out portion in one end extending from one cutting edge to approxi-
mately the longitudinal center thereof, one of said cutting edges on the stationary blade having an inwardly turned lip at one side 50 of the cut-out to cooperate with the curved end of the movable blade, and securing means passing through the body portion and engag-
ing said last mentioned blade approximately along its central line. 55

In testimony that I claim the foregoing I have hereunto set my hand at Racine, in the county of Racine and State of Wisconsin.

ROBERT HEINRICH.
